UNITED STATES PATENT OFFICE.

ADELE DUVALL, OF CHICAGO, ILLINOIS.

UNDERWEAR.

1,352,944.

Specification of Letters Patent. Patented Sept. 14, 1920.

Application filed April 9, 1917. Serial No. 160,672.

To all whom it may concern:

Be it known that I, ADELE DUVALL, a citizen of the United States, and a resident of the city of Chicago, in the county of Cook and State of Illinois, have invented 5 certain new and useful Improvements in Underwear; and I do hereby declare that the following is a full, clear, and exact description of the same, reference being had 10 to the accompanying drawings, and to the numerals of reference marked thereon, which form a part of this specification.

This invention relates to an improved article of underwear particularly adapted for use 15 by women, and designed for the utmost convenience and comfort of the wearer. The ordinary type of women's union suits possess many disadvantages, but, by my invention, I overcome these disadvantages by constructing a garment substantially the same 20 as the usual type of union suit but with the further addition or provision of a short skirt section preferably woven integral with or securely stitched to the garment though 25 not necessarily so, and disposed at the back of the garment so that when the garment is worn, the skirt portion hangs downwardly from slightly below the waist line to a point slightly above the knees, fitting comfortably 30 over and around the buttocks of the wearer and held extended around the sides by the manner of fastening.

It is an object therefore of this invention to provide an underwear garment of an 35 improved construction utilizing an auxiliary skirt section integral with the garment securely stitched thereto or detachably connected thereto, as desired.

It is also an object of this invention to 40 construct an improved type of underwear garment consisting in combination with a union suit of a skirt section secured slightly below the waist line of the garment at the back thereof, and attached thereto on downwardly curving lines along the sides of the garment, and depending from the points of attachment with the sides and bottom edges of said skirt free to a point slightly above the knees of the wearer.

50 It is furthermore an object of this invention to construct an under garment for women's wear comprising a union suit portion provided with a skirt section secured to or woven integral therewith, said skirt 55 section attached along its top edge which

curves downwardly from the rear slightly forwardly along the sides of the garment and depends freely with the side edges and bottom edge unattached, to a point slightly above the knees of a wearer.

It is finally an object of this invention to construct an improved type of under garment embracing in combination with a close fitting suit portion, a skirt seat section freely depending at the back thereof.

The invention (in a preferred form) is illustrated in the drawings and hereinafter more fully described.

In the drawings:

Figure 1 is a side view of a person wearing a garment embodying the principles of my invention.

Fig. 2 is a side and rear view of the person wearing the garment.

Fig. 3 is a side view of the complete garment with the lower half shown in central vertical section.

Fig. 4 is a detail section view illustrating the integral interwoven attachment of the skirt section to the main body portion of the garment.

Fig. 5 is a modified view illustrating the skirt section stitched to the main portion of the garment.

Fig. 6 is a view of a person seated in a chair wearing the garment illustrating the disposition of the parts.

As shown in the drawings:

The reference numeral 1, indicates the body portion of a garment above the waist line of a wearer, and 2, the leg portions of the garment, with the crotch between said leg portions 2, entirely open from the front to the rear of the garment, as designated by the reference numeral 3, and shown in Fig. 3. The skirt section, which is woven integral with the garment 1-2 or, if desired stitched or attached thereto, in any manner, is denoted as a whole by the reference numeral 4, and is provided with a substantially straight upper edge 5, which curves downwardly on each side as designated by the reference numerals 6, at the point of connection with the back of the garment, the curved edges 6 at the upper end of said skirt section also leading slightly forwardly along the sides of the garment as well as downwardly, so that when the wearer sits down the forward connection at the upper edge tends to pull somewhat on the 110

sides of the apron or skirt section and causes same to fit smoothly under the body when in the sitting position.

In the modified form of device shown in Fig. 5, the main garment is denoted as a whole by the reference numeral 7, and the skirt section by the reference numeral 8, and the skirt is attached along its upper edge by a line of stitching 9.

10 The operation is as follows:

In all positions of the wearer, the skirt section 4, on the undergarment is disposed close to, though not necessarily in contact with the upper extremities of the limbs of the wearer, that is, depending freely therefrom with the wearer in a standing position and, when the wearer is seated, held closely inwardly beneath the person by the skirts or other outer garments worn. The skirt section 4, serves effectually to prevent contact of other garments worn by the person, with the body along the open crotch portion 3, of the garment 1—2, in the different postures assumed by the person, so that protection is not only afforded the body of the person by the skirt section 4, but the outer garments of the wearer are also protected from direct contact with the body.

I am aware that various details of con-

struction may be varied through a wide range without departing from the principles of this invention, and I therefore do not purpose limiting the patent granted otherwise than necessitated by the prior art.

I claim as my invention.

An undergarment having a crotch opening, an apron adapted to conceal and cover said opening, said apron extending to approximately the knees of the wearer and being attached by a line of stitching or its equivalent to the back of the undergarment on a line immediately below and parallel with the waist line thereof, said line of stitching being thence curved forwardly and downwardly to approximately half-way around the garment to substantially the axis of the hip joints on either side of the leg portions thereof, whereby a close fitting of the apron to the body of the wearer is insured in all postures.

In testimony whereof I have hereunto subscribed my name in the presence of two subscribing witnesses.

ADELE DUVALL.
